UNITED STATES PATENT OFFICE.

VIRGIL LEROY HUDSON, OF TULSA, OKLAHOMA, ASSIGNOR OF ONE-HALF TO ALICE BEST, OF TULSA, OKLAHOMA.

PUMPING JACK.

Application filed October 5, 1925. Serial No. 60,668.

This invention relates to an improvement in pump jacks of the type forming the subject matter of Patent #1,211,529.

The object of the invention is to provide a pump jack having all the advantages and capacities of this type of pump jack and which imparts a true rectilinear movement to the polish rod thereby relieving the polish rod and parts of the pump jack of strain and preventing wear of the polish rod and stuffing box.

A further object resides in the provision of a device of this character which is of simple, strong and durable construction, reliable and effective in operation and easy and comparatively inexpensive to manufacture.

Other objects and advantages reside in certain novel features of the construction, arrangement and combination of parts as will be hereinafter more fully described and particularly pointed out in the accompanying drawings forming part of this specification and in which:

Figure 1 is a view in side elevation showing a pump jack constructed in accordance with the present invention.

Figures 2 and 3 are detail views in front and side elevation respectively showing the swingable hanger hook of pump jack.

Figure 4 is a plan view of the bearing for the hanger hook.

Figure 5 is a view thereof in longitudinal central vertical section, and

Figure 6 is a view thereof in front elevation.

Referring to the drawings the numeral 1 designates the frame of the pump jack at the upper end of which bearings 2 are provided. Trunnions 3 carried by the block of a walking beam 4 are rotatably mounted in the bearing 2 of the frame whereby the walking beam is mounted for rocking movement about a fixed axis.

Means designated generally at M is provided for rocking or oscillating the walking beam and for a full disclosure of this means reference is made to Patent #1,211,529.

The present invention resides in the provision between the walking beam 4 and a polish rod 5 of motion transmission means of such a character that the rocking movement of the walking beam will be applied as a right line movement to the polish rod. For this purpose the outer end of the walking

beam has a bearing 6 mounted and fixed thereon. The bearing 6 has a body plate 7 spanning and secured to the channel side bars 4^a of the walking beam and forwardly of the plate 7 the bearing 6 is bifurcated to provide spaced side members 8 which rest on the bars 4^a and which have transversely aligned recesses or bearing surfaces 9.

A swingable hanger hook 10 is provided and has a bar like body portion 11 to the upper end of which a transverse shaft 12 is fixed. The ends of the shaft 12 are journaled in the bearing surfaces 9. The lower portion of the hook is in the form of a yoke having curved arms 13 constituting the bill of the hook. Recessed bearing surfaces 14 are formed in the arms 13 and receive oppositely extending trunnions 14 fixed on and projecting laterally from the sections of a clamp 16 secured to the polish rod 17 by suitable clamping nuts and bolts. The polish rod reciprocates through a stuffing box 19 provided on the casing head 20.

An adjustable abutment is provided for limiting the inward swinging movement of the hanger hook and this abutment preferably comprises an abutment plate 20 adjustably secured to a U-shaped bracket 21 mounted between and fixed to the bars 4^a of the walking beam. For adjustably securing the plate 20 to the bracket 21 a bolt and nut 22 is provided, the bolt extending through a bolt hole in the bracket and through a slot 23 in the plate 21.

The abutment plate 21 is secured in such position on its bracket 22 that the body portion of the hook engages the outer end of the plate 21 to limit its swinging movement toward the walking beam when the body portion 11 of the hook is in a vertical position and when the walking beam is in a horizontal position.

With this arrangement the rocking movement of the walking beam 4 is translated into a straight line vertical movement when applied to the polish rod. The translation of this curvilinear motion of the walking beam into a rectilinear movement in the polish rod is effected by virtue of the fact that the hanger hook 10 swings to compensate for the swinging of the walking beam during the phases of movement of the walking beam below its horizontal position. Above its horizontal position the outer end of the walking beam recedes slightly from

the polish rod but due to the downward offsetting of the arms 13 which connect with the trunnions 14 and also by virtue of the engagement of the hook with the abutment 5 the arms 13 still swing outwardly to such an extent as to compensate for the inward swing of the outer end of the walking beam.

In this way the polish rod 17 is not flexed laterally but reciprocates vertical through 10 its stuffing box 19 and wear on these parts is prevented.

I claim:

1. A pump jack having a walking beam rockable about a fixed axis, a hanger hook 15 swingably mounted on the walking beam and adapted to be connected to a polish rod, and an abutment for limiting the swinging movement of the hook toward the walking beam.
- 20 2. A pump jack having a walking beam rockable about a fixed axis, a hanger hook swingably mounted on the walking beam and adapted to be connected to a polish rod, and an abutment for limiting the swinging 25 movement of the hook toward the walking beam, said abutment comprising a bracket fixed on the walking beam, a plate adjustable on the bracket and means for fastening the plate in adjusted position on the bracket.
- 30 3. A pump jack having a walking beam rockable about a fixed axis, a hanger hook swingably mounted on the walking beam and having curved arms constituting a bill and provided with bearing surfaces, and a 35 clamp adapted to be secured to a polish rod and having trunnions engaged with the bearing recesses of the arms.
4. A pump jack having a walking beam rockable about a fixed axis, a hanger hook

swingably mounted on the walking beam 40 and having curved arms constituting a bill and provided with bearing surfaces, and a clamp adapted to be secured to a polish rod and having trunnions engaged with the bearing recesses of the arms and an adjustable 45 abutment for limiting the inward swinging movement of the hook toward the walking beam.

5. A pump jack having a walking beam rockable about a fixed axis, a hanger hook 50 having a transverse shaft fixed to its upper end and swingably mounted on the walking beam and having curved arms constituting a bill and provided with bearing surfaces and a clamp adapted to be secured to a polish 55 rod and having trunnions engaged with the bearing recesses of the arms.

6. A pump jack having a walking beam rockable about a fixed axis, a hanger hook having a transverse shaft fixed to its upper 60 end, a bearing mounted on the walking beam and including a body plate and side members formed with bearing recesses receiving the ends of the shaft, said hook also having curved arms constituting a bill and provided with bearing surfaces, and a clamp 65 adapted to be secured to a polish rod and having trunnions engaged with the bearing recesses of the arms.

7. In a pump jack, the combination of a 70 walking beam, a pendent swingable member pivotally connected at one end portion of the beam and having a bifurcated hook, and a polish rod having lateral projections, said rod disposed in said bifurcation and said 75 lateral projection disposed in the bill portions of the hook.

VIRGIL LEROY HUDSON.
